UNITED STATES PATENT OFFICE.

LEWIS L. MOORE, OF CANTON, OHIO, ASSIGNOR TO MORDECAI MOORE, OF CANTON, OHIO.

SHIRT-SLEEVE.

974,692.

Specification of Letters Patent.

Patented Nov. 1, 1910.

Application filed February 19, 1910. Serial No. 544,912.

To all whom it may concern:

Be it known that I, LEWIS L. MOORE, a citizen of the United States, residing at Canton, in the county of Stark and State of Ohio, have invented certain new and useful Improvements in Shirt-Sleeves, of which the following is a specification.

The invention relates to the sleeve of a shirt or other similar garment.

10 The common practice of providing a slit or vent in one side of the free end of a sleeve, to permit the same to pass over the hand, is objectionable for the reason that even though the cuff portion of the sleeve 15 be closed and fastened around the wrist, the portion of the vent above the cuff permits dust and dirt to enter the sleeve and soil the arm or the sleeve of the under-garment; and, if the sleeve is made large enough to slip 20 over the hand without means for constricting it around the wrist, free dust and dirt is permitted to pass upward through the interval between the cuff and the wrist. Furthermore, when a slit sleeve is used, it is 25 impossible to push the sleeve above the elbow and retain it in such position, as for washing the wrist and arm, except by rolling the lower end of the sleeve upward upon itself.

The object of the present invention is to 30 make a sleeve without any slit in its free end, adapted to pass freely over the hand and elbow, and to provide the end of the sleeve with a peculiar form of cuff by means of which the end of the sleeve can be neatly 35 folded and snugly closed and fastened around the wrist.

A preferred embodiment of the invention is illustrated in the accompanying drawing, forming part hereof, in which—

40 Figure 1 is a perspective view of the free end of the sleeve showing the cuff thereon and open; Fig. 2, a section through the cuff portion of the sleeve showing the folds of the same when closed and fastened; Fig. 3, 45 a perspective view of the sleeve on an arm with the cuff portion folded, closed and fastened around the wrist; Fig. 4, a perspective view showing the sleeve on an arm with the cuff portion open and pushed above the 50 elbow; and Fig. 5, a modified form of the cuff, showing the use of elastic material in the free end thereof.

Similar numerals refer to similar parts throughout the drawing.

55 The sleeve 1 is preferably made with the

longitudinal seam 2 along the rear side thereof in which seam one end 3 of the cuff 4 is preferably secured. The cuff extends in width a substantial distance upward from the edge of the sleeve, and extends in length from the longitudinal seam around the free end of the sleeve, inward and forward and then outward and rearward, in the usual manner; but is secured to and reinforces the sleeve, as by stitching 60 or otherwise, only part way around the same, to a longitudinal line 6—6 some distance forward from the longitudinal seam, thus leaving the plain portion 7 of the sleeve free from the reinforcement of the cuff, which 65 plain portion of the sleeve is preferably a single ply of the material thereof, while the secured portion of the cuff makes a plurality of plies of the material. The free end 8 of the cuff is extended rearward beyond the 70 line of its attachment to the sleeve, in which free end is formed the buttonhole 9 which is adapted to engage the button 10 located on the secured end portion of the cuff at an interval in rear of the longitudinal seam. 75 With this arrangement of the parts, it is evident that when the free end of the cuff is disengaged from the button, the end of the sleeve is permitted to expand for passing over the hand or elbow, and that the cuff 80 can be closed snugly around the wrist and fastened by engaging the free end thereof on the button, in doing which the intervening portion of the sleeve readily folds along the longitudinal seam and the adjacent securing line of the free end of the cuff, so 85 that only the normal or single thickness of the plain portion of the sleeve intervenes between the overlapping plural-ply portions of the cuff, as shown in Fig. 2; which insures a flat and neat folding of the cuff and adjacent portion of the sleeve, and a complete closure of the free end of the sleeve around the wrist. And it will be understood that the sleeve can be worn without 90 closing the cuff around the wrist, as in warm weather or when the fastening means are detached, without the objectionable opening to which a slit sleeve is subject.

It is evident that the scope of the invention is not limited to the use of a button-hole and button as means for fastening the cuff when clamped around the wrist. In the modified form of cuff shown in Fig. 5 the extended free end or section 8^a of the cuff is 105 110

formed of elastic material which gives the cuff an expansive adjustment, and two fastenings 9^a and 10^a of a modified form are shown. When the free section of the cuff is made of elastic material, it is not necessary to disconnect the fastening of the same for passing the free end of the sleeve over the hand or elbow.

I claim:

- 10 1. A shirt sleeve having a cuff on its free end extending from the edge a substantial width upward therefrom, the cuff being secured to the sleeve and forming a reinforced portion with a plural-ply of material part way around the same, there being a single-ply portion of the sleeve intervening between the ends of the reinforced portion thereof, and one end of the cuff being extended from its secured portion and adapted to overlap the other secured end, with means 15 for fastening the overlapped portions of the cuff, whereby the single-ply portion of the
- 20

sleeve is neatly folded between the reinforced portions thereof.

2. A shirt sleeve having a cuff on its free end extending from the edge a substantial width upward therefrom, the cuff being secured to the sleeve and forming a reinforced portion with a plural-ply of material part way around the same, there being a single-ply portion of the sleeve intervening between the ends of the reinforced portion thereof, and one end of the cuff being made of elastic material and extended from its secured portion and adapted to overlap the other secured end, with means for fastening the overlapped portions of the cuff, whereby the single-ply portion of the sleeve is neatly folded between the reinforced portions thereof.

LEWIS L. MOORE.
